UNITED STATES PATENT OFFICE

CONRAD R. VEGREN, OF CHICAGO, ILLINOIS

CAR DOOR LOCK

Application filed April 16, 1931. Serial No. 530,508.

This invention relates to locks for car doors.

It is an object of the invention to provide a lock for car doors by which said doors may 5 be forced into their fully closed position.

A further object is the provision of a lock for car doors, which will insure maintenance of said doors in fully closed position.

Other objects of the invention will become 10 apparent from the following description thereof:

In the drawings forming a part of the specification,

Figure 1 is a fragmentary elevation of a 15 car door lock embodying this invention in its application to a double door construction, the lock being shown in operative position.

Figure 2 is a view similar to Figure 1, illustrating the lock in inoperative position.

Figure 3 is a view similar to Figure 1, 20 showing the hasp of the lock in operative position and the locking pin partly withdrawn to better illustrate the relationship of the pin and the hasp.

Figure 4 is a sectional view taken on line 25 4-4 of Figure 1.

Figure 5 is a sectional view taken on line 5-5 of Figure 6.

Figure 6 is a sectional view taken on line 30 6-6 of Figure 4.

In the drawings the preferred embodiment 35 of the invention is shown in its application to a double door construction. It is to be understood, however, that the lock is not limited in its application to such double door construction but is capable of utility as well with a single door construction. In the double door structure illustrated there is provided a main door 10 and an auxiliary door

40 11. The auxiliary door may be supplied with a jamb 12 movable therewith and in which a filler post or nailing strip 13 may be seated. Stiffeners 14 may be utilized in the main and auxiliary doors.

45 Applied to the auxiliary door 11 is a lock

plate 15 which may be secured thereto by means of a plurality of rivets 16-16 extending through said lock plate, the door and a backing plate 17. The lock plate is provided with a guideway 18 adapted to slidably receive a locking pin 19. The lock plate 15 is further provided with a pair of vertically spaced flanges 20-21 extending forwardly thereof and connected by means of a retaining wall 22 which lies in spaced relation to the lock plate.

Secured to the main door 10 by means of a plurality of rivets 23 is a hasp fastener 24. The rivets 23 extend through said fastener, the door and the backing plate 25. Said fastener is preferably provided with a forwardly extending boss 26 upon which a hasp 27 is adapted to be supported. The hasp 27 is provided with an elongated slot 28 whereby said hasp is adapted to have both pivotal and sliding movement relative to said boss. The hasp is retained in position upon the boss by means of a washer 29 retained in position by means of a rivet 30. On the face of the hasp presented toward the door a recessed portion 31 is provided. By means of this recessed portion there is presented a pair of spaced substantially vertical walls 32 and 33, respectively, the latter of said walls or abutments being positioned preferably adjacent the free end of said hasp and being inclined.

The locking pin 19, as hereinbefore pointed out, is slidably retained in the guideway 18 provided in the lock plate 15. The pin 19 is additionally retained against removal from the guideway 18 by means of a boss 34 extending from said lock plate and through an elongated slot 35 formed adjacent the lower portion of said pin. A washer 36, larger in diameter than the width of the slot formed in the pin 19, is retained against the boss by means of one of the rivets 16, thereby preventing withdrawal of the pin from the guideway formed in the lock plate. Intermediate the ends of the pin a projection 37

70

75

80

85

90

is formed, this projection having spaced walls 38 and 39, the latter being inclined to the vertical in conformity with the inclined wall 33 provided on the hasp. The upper end of the pin is formed with a flange portion 40 and a flange portion 41 extending substantially at right angles to the flange portion 40 and provided with an opening 42. The flange portion 41 is adapted to be positioned adjacent the flange 43 provided on said lock plate and having an opening 44 aligned with the opening 42 provided in the flange portion 41 so that the seal (not shown) may extend through said aligned openings for sealing the door.

In order to close a door opening provided in a house car by means of the doors 10 and 11 the auxiliary door 11 will first be moved to closed position. The main door will then be moved toward closed position. Assuming, however, that the main door cannot be moved to its fully closed position the lock construction above described may be utilized for this purpose within the limits of the lock. To accomplish this result the hasp may be moved to the position shown in dot and dash lines in Figure 2 of the drawings and then moved substantially horizontally until it is positioned in supporting relationship upon the flange 21 and between the retaining wall 22 and the lock plate. Prior to this placement of the hasp the pin 19 will have been elevated to the position shown in Figure 2 of the drawings, the pin in this movement passing through a recess R, clearly shown in Figure 6 of the drawings and formed in the upper flange 20 of the lock plate. The pin will then be lowered until the projection 37 provided thereon enters the recessed portion 31 formed in the hasp. The pin may then be driven downwardly during which movement the hasp and, consequently, the door to which it is secured will be forced to fully closed position. This is effected by means of the engagement between the inclined wall 39 formed on the projection 37 and the inclined wall 33 provided by the recessed portion 31 on the hasp. For the purpose of driving said pin to home position the flange 40 is provided at the upper end thereof. It is apparent that when said door has once been drawn to its fully closed position it will be rigidly retained in such position against back-and-forth movement when the car is in transit. It is manifest from Figure 4 of the drawings that because of the engagement between the right hand end of the hasp and the boss formed on the hasp fastener no movement of the door toward the right can result. Furthermore, inasmuch as the two doors as shown in this figure are now in engagement the door 10 cannot move toward the left.

While a preferred embodiment of this invention has been set forth it is to be understood that the invention is not to be limited

to the details of construction shown. It is intended that all changes and modifications falling within the spirit of the invention are covered herein and that no limitations other than those included in the claims appended hereto are to be imparted to this invention. 70

I claim:

1. In combination, a relatively fixed member, a sliding door, a lock plate secured to said relatively fixed member, a hasp fastened secured to said door, a hasp supported by said fastener, said hasp adapted to engage said lock plate, an abutment provided on said hasp, a locking pin, and an abutment provided on said pin, said last mentioned abutment having a longitudinally inclined surface adapted to engage the abutment on said hasp for the purpose set forth. 75

2. In combination, a lock plate secured to a relatively fixed member, a hasp fastener secured to a relatively movable member, a hasp supported by said hasp fastener and adapted to engage said lock plate, said hasp being provided with a recessed portion including an inclined wall and a vertical wall and a locking pin having a similarly inclined wall and a vertical wall adapted to extend into said recessed portion. 80

3. In combination, a lock plate secured to a relatively fixed member, a hasp fastener secured to a relatively movable member, a hasp supported by said fastener and adapted to engage said lock plate, said hasp being provided with a recessed portion including an inclined wall and a vertical wall and a locking pin having a projection provided with a similarly inclined wall and a vertical wall adapted to extend into said recessed portion. 85

4. In combination, a lock plate secured to a relatively fixed member, a hasp fastener secured to a relatively movable member, a hasp slidably carried by said hasp fastener, a wall carried by said lock plate in spaced relation thereto, said hasp adapted to be supported between said lock plate and said wall by a sliding movement and a locking pin slidably carried by said lock plate and adapted to engage said hasp to maintain it in said position. 90

5. In combination, a lock plate secured to a relatively fixed member, said lock plate comprising a retaining guideway, vertically spaced flanges extending from said lock plate, a wall spaced from said lock plate connecting said flanges, a hasp fastener secured to a relatively movable member, a hasp provided with an inclined abutment slidably carried by said fastener, said hasp adapted to be supported upon one of said flanges between said lock plate and said wall and a locking pin slidably retained in said guideway and provided with a similarly inclined abutment adapted to engage the abutment on said hasp, the upper of said spaced flanges being cut away to permit such engagement. 115

6. In combination, a lock plate secured to a 120

relatively fixed member, a hasp fastener secured to a relatively movable member, a hasp carried by said hasp fastener, said lock plate comprising a supporting flange and retaining means extending from said flange in spaced relation to said lock plate, an abutment provided on said hasp, said hasp adapted to be supported upon said flange and behind said retaining means and a locking pin adapted to be positioned between the inner face of said hasp and said lock plate in engagement with said abutment.

Signed at Chicago, Illinois, this 14th day of April, 1931.

CONRAD R. VEGREN.
